Willard Sawyer, Nutley, N. J.

Application February 21, 1945, Serial No. 579,048

5 Claims. (Cl. 108—6)

1

This invention relates generally to roofing and more particularly to improved construction for connecting the foundation layers of a composition or water proofed roof with a vertical wall, a chimney, parapet and the like to prevent leaks.

An object of the present invention is to provide a strong, durable and efficient weather-proof connection between the roof and the building walls.

Another object is to provide roofing which is cheap, easily laid and of considerable rigidity and which is produced of ingredients which are available at low prices.

Still another object is to provide a construction that eliminates the necessity for anchoring devices, nails or the like.

A further object is to provide roofing that may be successfully secured to a wall of concrete or the like and may be readily connected to either a new or an old wall.

The invention will be better understood from the description thereof to follow taken in connection with the accompanying drawing in which—

Figure 1 is a fragmentary sectional view taken through the vertical wall of a building and the roof thereof showing the main roofing material connected to the wall by a construction embodying the present invention.

Figure 2 is a sectional view taken on the plane of the line 2—2 of Figure 1.

Referring to the drawing, a vertical wall 5 of concrete or any other suitable material is shown formed with an integral roof deck 6. A parapet 7 of brick is built on top of the wall and on top of the parapet is a coping 8.

The roof deck is covered with a composition roofing material preferably formed of a plurality of superimposed layers or plies of asphalt or pitch and felt or paper. A coating 9 of asphalt or pitch covers the upper surface of the roof. A layer or ply 10 of felt or paper is laid over the coating 9. Another layer or ply 11 of asphalt or pitch covers the felt 10. Still another layer or ply 12 of felt is superimposed upon the asphalt 11 and this felt 12 is covered by a layer or ply 13 of asphalt or pitch. These layers comprise the main portion of the roof and while five layers or plies of asphalt and felt including the coating are illustrated, it will be understood that any desired number of layers may be used. This roofing material, comprising the layers of asphalt and felt however, does not extend to the vertical wall 5 but ends at a point remote therefrom as indicated at 14, leaving a space between the end of the material and the wall.

2

The present invention is concerned with means for preventing moisture from entering under said roofing material from the parapet and contemplates a construction formed of a plurality of superimposed layers or plies of asphalt, pitch or the like and of felt, paper or the like. In accordance with the present invention, a layer or ply 15 of asphalt or pitch, which is similar to or may be actually a continuation of the layer 9, is placed over 5 the upper surface of the concrete roof 6 in the space between the end of the roofing material and the wall 5. A layer or ply 16 of felt or paper is next laid or embedded flatwise over the asphalt or pitch 15, the inner edge of the felt 16 being 10 positioned adjacent the outer edge of the roofing material and its outer edge abutting against the inner surface of the wall. Another layer or ply 17 of asphalt or pitch overlies the felt layer 16, said layer 17 extending across the edge 14 of the 15 main portion of the roof and directly merging into or contacting with the upper layer 13 of asphalt on the main portion of the roof and having its outer edge abutting against the wall. A strip 18 of felt or paper is laid on said layer 17 of 20 asphalt in overlapping relation to the joint between the ply 9 of the main portion of the roof and the ply 16 of the flashing. Another layer 19 of asphalt overlies the strip 18 and merges into the asphalt layer 17 at opposite edges of said strip. Another ply or layer 20 of felt overlies the 25 asphalt layers 17 and 19 and has its outer edge abutting against the wall, and its inner edge curved downwardly in overlapping relation to the edge of said strip 18 and into contact with the asphalt layer 13. This layer 20 is topped by another layer or ply 21 of asphalt or pitch whose, 30 inner edge is bent around and over the inner edge of layer 20 and engages directly on the top surface of the asphalt layer 13, the outer edge thereof abutting against the wall. Still another layer or 35 ply 22 of felt overlies the asphalt layer 21 and its inner edge is bent and curved downwardly directly engaging the top layer 13 of asphalt with its outer edge abutting against the wall. The felt 40 layer 22 is overlaid by a layer or ply 23 of asphalt which extends over the inner edge of the felt ply 22 and onto the asphalt layer 13 and has its outer edge abutting against the wall. It will be noted that the outer edges of the layers or plies all abut 45 against the inner surface of the wall so that a cemented sealed moisture-proof joint is formed between the roofing and wall. The downwardly curved inner ends of the layers provide a slanting surface for shedding the surface water and 50 the enlarged inner edge of the topmost asphalt 55

layer enhances the binding of the roofing at this point. The wall is exposed or uncovered upwardly from the top surface of the layer 23.

The composite roofing herein described can be used to good advantage in any place in new or existing work where a flashing ordinarily would be used, more easily and safely than flashings now in use. It eliminates the necessity for anchoring devices for locking the flashing into the wall and also eliminates specially designed strips that are built into the wall to receive flashings. The roofing can be built up to a point much higher than is usual above horizontal surfaces with but very slight additional expense because of the cheapness of the asphalt and felt as compared with metal. The specific embodiment of the invention is especially advantageous in patching existing or old roofs, the flashing being removed and the roofing material being cut away to leave edges in spaced relation to the parapet, as indicated at 14, after which the plies 15—23 inclusive are applied as a border for the old roofing material.

While the roofing material covering the main portion of the roof has been shown as composed of five plies and the border composed of seven plies, it will be understood that the border preferably will be composed of a plurality of plies equal in number at least to the number of plies of the roofing material on the main portion of the roof although any additional number of plies may be used for the flashing as desired. Preferably the aggregate thickness of the layers of the border are equal to or greater than the thickness of the main portion of the roofing material to ensure adequate drainage from the border.

Changes in details might be resorted to without departing from the scope of the invention and it is desired to be limited only by the state of the prior art and the appended claims.

To avoid circumlocution, in the claims, the terms "asphalt" and "felt" are intended to include all equivalents of or substitutes for, or all materials which will serve the same purpose as "asphalt" and "felt" respectively.

We claim:

1. The combination of a roof deck and an upstanding wall connected thereto, a composite roofing secured on said roof deck and comprising a plurality of superposed alternate plies of asphalt and felt the outer margins of which have an edgewise abutting and watertight sealed contact with said wall, said wall being uncovered upwardly from said roofing.

2. The combination of a roof deck having an upstanding wall connected thereto, a composite main portion of roofing material covering the area of said roof deck to a point remote from said wall, leaving a space between said main portion and said wall, and a border for connecting said main portion to the wall comprising a plurality of superimposed alternate layers of asphalt and felt laid on said roof deck in the space between said main portion and said wall, the outer margins of said layers having an edgewise abutting and cemented watertight joint with said wall and the inner margins of at least some of said layers overlapping the edges of said main portion, said wall being uncovered upwardly from the top surface of said border.

3. The combination of a roof deck and an up-

standing wall connected thereto, a composite main portion of roofing material including a facing that contains asphalt covering the area of said roof deck to a point remote from the wall, leaving a space between said main portion and said wall, and a border for connecting said main portion to the wall comprising a plurality of superimposed alternate layers of asphalt and felt interposed in the space between said main portion and said wall, the outer margins of said layers having an edgewise abutting and cemented watertight joint with said wall, the inner margins of some of said layers slanting downwardly and engaging said main portion, the topmost layer being formed of asphalt and having its inner edge merging into said facing layer of asphalt on said main portion, said wall being uncovered upwardly from the top surface of said border.

4. The combination with a roof deck and an upstanding wall connected thereto, of a composite main portion of roofing material covering the area of said roof deck to a point remote from the wall, leaving a space between said main portion and wall, a border for connecting said roofing material to the wall comprising a coating of asphalt on the roof in the space between said main portion and said wall, a layer of fibrous material over said asphalt with its outer edge abutting against the wall and its inner edge positioned adjacent the outer edge of said main portion, a layer of asphalt overlying said fibrous material and said edge of said main portion, a strip of fibrous material overlying the joint between said main portion and said fibrous layer, a layer of asphalt overlying said strip of fibrous material and having its outer edge abutting against the wall and its inner edge curving downwardly over the inner edge of said strip and directly engaging said main portion, and a plurality of alternate layers of fibrous material and asphalt superimposed on said first-named asphalt layer, the outer margins of said last-named layers having an edgewise abutting and water-tight sealed contact with the wall and their inner margins being curved downwardly, the topmost layer thereof comprising asphalt and having its inner edge in engagement with said main portion, said wall being uncovered upwardly from the top surface of said border.

5. A roofing construction comprising a roof deck having a parapet at one edge thereof, a plurality of superimposed alternate layers of asphalt and felt covering the area of the roof deck to a point remote from the parapet, and a border construction in the space between the edges of said layers and the parapet including a plurality of superimposed alternate plies of asphalt and felt of an aggregate thickness equal at least to the thickness of the remaining area of roof, the outer margins of all of the plies of the border construction having an edgewise abutting and cemented watertight joint with the parapet, the inner edges of a plurality of said plies overlapping the outer edges of the first-named layers, and each of a plurality of said plies of the border construction overlapping the inner edge of the next lower layer, said parapet being uncovered upwardly from the top surface of said border.
